MECHANICAL TIME FUSE

Marvin L. Mathsen, Wharton, and Archibald E. Reinhard, Dover, N. J., assignors to the Government of the United States of America, represented by the Secretary of War

Application October 1, 1937, Serial No. 166,772

19 Claims. (Cl. 102—36)

(Granted under the act of March 3, 1883, as amended April 30, 1928; 370 O. G. 757)

The invention described herein may be manufactured and used by or for the Government for governmental purposes, without the payment to us of any royalty thereon.

5 The subject of this invention is a mechanical time fuse.

The purpose of the invention is to provide a rugged and waterproof mechanical time fuse which will meet a large number of requirements 10 relating to safety and to functioning. The fuse is so constructed that commencement of flight is necessary for partial arming and impact is necessary to permit starting of the clockwork movement which must run for a period of approximately five minutes before permitting a detonator to be moved into line with a firing pin.

A further object of the invention is to provide 20 a simple and efficient connection between the timing lever and a lever which restrains the firing pin whereby the firing pin spring exerts its influence to hold the timing lever against a setting disk.

Other objects of the invention are to provide 25 means, functioning at the commencement of flight for locking the cover of the fuse casing and for locking the fuse casing to the bomb body.

To these and other ends, the invention consists in the construction, arrangement and combination of elements described hereinafter and 30 pointed out in the claims forming a part of this specification.

A practical embodiment of the invention is illustrated in the accompanying drawings, wherein:

35 Fig. 1 is a longitudinal sectional view, partly in elevation of the improved fuse, the section being taken on the line 1—1 of Fig. 5.

Fig. 2 is a sectional view taken on the line 2—2 of Fig. 5.

40 Fig. 3 is a sectional view on the line 3—3 of Fig. 2.

Fig. 4 is a sectional view on the line 4—4 of Fig. 3.

Fig. 5 is a plan view with the cover removed.

45 Figs. 6, 7 and 8 are sectional views on the corresponding lines of Fig. 2.

Fig. 9 is a sectional view on the line 9—9 of Fig. 5.

Fig. 10 is a plan view, with the cover removed, 50 of a modified form of the invention.

Fig. 11 is a sectional view on the line 11—11 of Fig. 10.

55 Figs. 12 and 13 are sectional views on the corresponding lines of Fig. 10.

The fuse casing comprises an inner portion 5

(Figs. 1 and 2), and an outer portion 6, the inner portion being inserted in and threaded attached to a bomb body 1, and the outer portion being considerably larger in diameter and closed by a removable cover 8 which is threaded in place and 5 confines a packing ring 9. The outer portion carries a pawl 10 (Fig. 1) which is acted on by a spring 11 to hold it in engagement with the bomb and prevent removal of the casing from the 10 bomb. An aperture 12 in the side wall of the outer portion 6 provides for insertion of a rod or similar article to move the pawl out of engagement with the bomb, but this can only be accomplished when the cover 8 is removed.

The casing houses a more or less conventional 15 clockwork movement including a barrel 13 fixed in place in the outer portion by screws 14 and enclosing a spiral main spring 15. The main spring drives a hollow spindle 16 which, through gearing 17 (Fig. 4) drives gearing 18 on a spindle 20 19 passing through the hollow spindle 16. The usual regulating gear trains including escapement control are carried in a series of disks 20 which are disposed in the inner portion 5 of the casing and are mounted on rods 21 seated in the 25 barrel 13. The disks are confined between the barrel and a block 22 in which the rods are threaded. A setting disk 23 fixed on the outer spindle 16 has a marginal scale 24 (Fig. 5) graduated in "hours" and a setting disk 25 fixed on 30 the inner spindle 19 has a marginal scale 26 graduated in "minutes."

The block 22 is provided on its inner side with a recess 27 which is conveniently formed by interposing a segment of a ring 28 between the block 22 and a thin disk 29, the ring and disk being secured to the block by means of screws 30 (Fig. 8). A firing pin 31 mounted in the block has a tapered shoulder 32 adjacent the point on its inner end. The firing pin is normally held in 35 the safe or retracted position against the influence of a firing pin spring 33 by means of a pair of levers 34 and 35 which are disposed in the recess 27 and are mounted respectively on pivot pins 36 and 37 threaded in the block. The inner 40 ends of the levers are preferably beveled and adapted to engage the tapered shoulder 32 of the firing pin. The point of the firing pin is normally disposed in an aperture 38 in a diaphragm 39 of the inner portion 5 of the fuse casing.

A rotor 40 (Figs. 2 and 7) disposed in a chamber 41 between the diaphragm and a closure plate 42 is mounted on a pivot pin 43 and carries a detonator 44. The rotor is held in the unarmed position with its detonator out of line with the 55

firing pin by means of the segmental inner end 45 of a starter control rod 46. When the segmental end is turned out of engagement with a nose 47 of the rotor, the rotor is free to be rotated by its spring 48 to position the detonator in line with the firing pin. As seen in Fig. 8 the inner end 45 of the rod is also engaged by the outer end of the lever 34 and serves to oppose movement of the lever.

10 The rod 46 passes through the block 22 and disks 20 and its outer end is formed into a head 49 (Fig. 2) which is normally disposed in the barrel 13 and supported by a shearable washer 50. The washer is held in place by a hollow plug 51 which encloses the head 49. A segmental gear 52 (Figs. 3 and 4) is provided on the rod adjacent its head and is in mesh with an elongated pinion 53 which in turn is in mesh with the gearing 18. A pin 54 (Fig. 6) fixed transversely in the rod has projecting ends disposed in slots 55 in one of the disks 20 whereby the rod is held against rotation. For purposes of assembly each disk is formed with the slots 55. On impact the rod shears the washer 50 and moves longitudinally to 25 remove the pin 54 from the slots. The rod is now free to be rotated by the clockwork movement, whose starting is controlled, and after pre-determined interval, 4½ minutes in the present example, the rod has been turned sufficiently to 30 release the rotor 40 and the lever 34.

30 The rod 46 is additionally held against longitudinal movement by an arming mechanism which includes a plunger 56 (Figs. 2 and 4) mounted in a passage in the outer portion 6 of the casing and arranged perpendicular to the rod. The inner end of the plunger is insertable in an aperture 57 in the rod while the intermediate portion of the plunger includes a collar 58 acted on by a spring 59 normally tending to withdraw the 35 plunger from the rod. The collar has a sharp outer edge 60 (Fig. 2) adapted to be forced into a washer 61 to establish a fluid seal when the plunger is moved by its spring. The outer portion of the plunger passes through a plug 62, supporting the washer 61, and its extremity is 40 engaged by a second plunger 63, perpendicular to the first plunger, and carried in a bracket 64 attached to the fuse casing.

45 The plunger 63 is held in position to oppose withdrawal of the plunger 56 from the starting rod by means of an arming bolt 65 (Fig. 2) mounted in a laterally projecting tube 66. The outer end of this tube is threaded to permit the addition of a similar tube and an increase in 50 length to adapt it for bombs of larger sizes. The arming bolt is held by a cotter pin 67 when in storage but when the bomb is placed in the rack of aircraft, the cotter pin is removed and the arming bolt is held by the arming wire 68 which 55 is withdrawn in the well known manner when the bomb is launched from the aircraft. The adjoining ends of the arming bolt 65 and the plunger 63 are conical so that when the arming bolt has been freed by withdrawal of the arming wire 60 it may be moved aside by the plunger 63 which 60 is ejected from the fuse casing by its spring 69, thereby releasing the plunger 56.

65 A bolt 70 mounted in the fuse casing adjacent and parallel to the plunger 63, is normally held 70 in retracted position, against the action of a spring 71, by means of a ball 72. The ball is adapted to engage a shoulder 73, formed by reducing the bolt, and is held in engagement therewith by the plunger 63. On removal of the 75 plunger 63, the bolt is moved by its spring and

forces the ball to one side into a recess 74. When the bolt is released its outer end engages the cover 8 where it enters one of an angular row of recesses 75 in the cover or is positioned between the recess so that any attempt to unscrew the 8 cover will result in its engagement in one of the recesses.

A timing lever 76 (Figs. 1, 5 and 9) fixed to a pivot pin 77 which is mounted in the barrel 13 carries an upstanding finger 78 which is adapted 10 to ride on the periphery of the setting disks 23 and 25 and to successively enter a wide-mouthed recess 79 in the disk 23 and a recess 80 in the disk 25. The timing lever is locked against movement by a pin 81 which is removed after the fuse 15 has been set for time functioning. The pin 81 passes through a setting indicator 82 fixed to the barrel, then through the timing lever 76 and then into the barrel. The indicator 82 includes a pointer 83 readable against the hour scale 24 20 and a pointer 84 readable against the minute scale 26.

The inner end of the pivot pin 77 which carries the timing lever has a semi-circular segment 85 which is arranged to engage the free 25 end of a lever 86. The pivot of the lever 86 consists of a long rod 87, quite similar to the starter control rod 46 and extending through the disks 20 and block 22, and terminates in a segment 88 (Fig. 8) which is disposed in the recess 27, and engages the outer end of the lever 35. The firing pin spring 33 acting through the firming pin tends to rotate the lever 35 and this influence is transmitted to the rod 87, the lever 86, and the pivot pin 77 and as a consequence 35 the finger 78 of the timing lever 76 is held against the periphery of the setting disks and caused to move into the recess of the disks. Conversely, the firing pin cannot move so long as the finger 78 rides on the periphery of the larger setting 40 disk 23 and it is not fully released until the finger enters the recess 80 in the smaller setting disk 25 at the expiration of the setting time.

The disks 23 and 25 are provided with apertures, respectively 89 and 90, for the application 45 of a wrench, not shown, whereby the disk may be manually set for a desired time of functioning which is indicated on the scales 24 and 26 by the pointers 83 and 84. In Fig. 5 the setting is for 50 minutes and 0 hours and as soon as the timing 50 lever is released by removal of the pin 81, the finger 78 moves through the recess 79 in the hour disk 23 and engages the periphery of the minute disk 25. After the fuse has been thus set the cover 8 is applied to the casing and the bomb is 55 ready to be launched.

When the bomb is launched, the arming wire 68 is automatically withdrawn and the plunger 63 being no longer held by the arming bolt 65 is ejected from the casing. The bolt 70 is now released to engage the cover and the plunger 56 is withdrawn from the starter control rod 46. The fuse is now only partially armed. On impact, the starter rod is driven forwardly and its pin 54 removed from the slots 55. The starter rod which 65 heretofore had held the clockwork movement is now rotated by said movement and at the end of 4½ minutes it has been turned sufficiently to release the rotor 40 and the lever 34.

The clockwork movement drives the setting 70 disks 23 and 25 and upon the expiration of the time set for functioning the entrance of the recess 80 of the disk 25 will be in position to receive the finger 78 of the timing lever. It is to be remembered that the lever 76 preliminary to its 75

ultimate release, must first enter the recess 78 of the hour setting disk 23, and this will of course be dependent on the setting of said disk. The timing lever is rotated as the firing pin spring 33 drives the firing pin into the detonator of the rotor in the manner previously described.

In the modification shown in Figs. 10-14 the arming bolt 91 extends into the fuse casing 92 and engages a yoke 83 carried by a guide pin 94. The yoke when engaged in this manner opposes movement of a pair of spring-pressed plungers 95 and 96 mounted in the fuse casing. One end of the plunger 95 is adapted, when the plunger is released, to engage and lock the cover 97 while the other end normally controls withdrawal of a plunger 98 from the starter control rod 99. The plunger 96 (Fig. 13) when restrained by the yoke engages a pawl 100 and serves to hold it out of locking engagement with the bomb. By virtue of this arrangement, the fuse may be removed from the bomb and replaced by a fuse of a different type at any time prior to actual launching of the bomb and release of the arming bolt.

The time functioning mechanism includes a single setting disk 101, graduated in hours, and having a recess 102 for reception of the timing lever 103. A spring-pressed plunger 104 mounted in the barrel 105 has a projecting finger 106 which is adapted to engage the disk 101 and be interposed in the path of movement of a lug 107 on the under side of the disk. The lug is so located that it will engage the finger and prevent rotation of the disk to a position which would allow the timing lever 103 to enter the recess 102. When the setting disk has been adjusted to the desired time of functioning by acting on the handle 108 the cover 97 is applied to the fuse casing and serves to displace the plunger 104 and remove the finger from the path of the lug. In this arrangement it is not necessary to employ the pin 81 of Fig. 9.

While the fuse is shown as applied to a bomb it may be readily adapted to projectiles fired from a barrel.

45 We claim.

1. In a fuse for bombs, a casing including a removable cover, a clockwork movement in the casing including a pair of setting disks each having a peripheral recess, a firing pin in the casing, a firing pin spring, a pair of levers for holding the firing pin in retracted position, a rotor having a detonator, a starter control rod engageable with the clockwork movement, the inner end of the rod including a segment for holding the rotor and one of the firing pin holding levers, means whereby the starter rod is held against rotation until it has been displaced longitudinally on impact, means releasable on launching of the bomb for holding the starter rod against rotational and longitudinal displacement, means associated with said preceding means for locking the cover to the casing, a timing lever adapted to ride on the periphery of the setting disks and to successively enter the recesses of said disks, a pivot pin for the timing lever having a segment, a rod having a segment on one end engageable with the other firing pin holding lever, and a lever on said rod engaging the segment of the pivot pin of the timing lever.

70 2. In a fuse for bombs, a casing including a removable cover, a clockwork movement in the casing including a timing lever having a segment, a firing pin in the casing, a firing pin spring, a pair of levers for holding the firing pin in retracted position, a rotor having a detonator,

a starter control rod engageable with the clockwork movement, the inner end of the rod including a segment for holding the rotor and one of the firing pin holding levers, means whereby the starter rod is held against rotation until it has been displaced longitudinally on impact, means releasable on launching of the bomb for holding the starter rod against rotational and longitudinal displacement, means associated with said preceding means for locking the cover to the casing, a rod having a segment on one end engageable with the other firing pin holding lever, and a lever on said rod engaging the segment of the timing lever.

3. In a fuse for bombs, a casing, a clockwork movement in the casing including a timing lever having a segment, a firing pin in the casing, a firing pin spring, a pair of levers for holding the firing pin in retracted position, a rotor having a detonator, a starter control rod engageable with the clockwork movement, the inner end of the rod including a segment for holding the rotor and one of the firing pin holding levers, means whereby the starter rod is held against rotation until it has been displaced longitudinally on impact, means releasable on launching of the bomb for holding the starter rod against rotational and longitudinal displacement, a rod having a segment on one end engageable with the other firing pin holding lever, and a lever on said rod engaging the segment of the timing lever.

4. In a fuse for bombs, a casing, a clockwork movement in the casing including a timing lever, a firing pin in the casing, a firing pin spring, a pair of levers for holding the firing pin in retracted position, a member carrying a detonator and movable to position the detonator in line with the firing pin, a rotatable starter control rod engageable with the clockwork movement, said rod adapted when restrained against rotation to hold the detonator member and one of the firing pin holding levers and adapted when rotated to control release of said member and lever, means whereby the starter control rod is held against rotation until it has been displaced longitudinally on impact, means releasable upon launching of the bomb for holding the starter control rod against rotational and longitudinal displacement, and a connection between the timing lever and the other firing pin holding lever whereby the timing lever is under the influence of the firing pin spring.

5. In a fuse for bombs, a casing, a clockwork movement in the casing, a firing pin in the casing, a firing pin spring, a pair of levers for holding the firing pin in retracted position, a rotatable starter control rod engageable with the clockwork movement and with one of the firing pin holding levers, said rod adapted when restrained against rotation to hold the clockwork movement and the lever and adapted when rotated by the clockwork movement to control timed release of said lever, means whereby the starter control rod is held against rotation until it has been displaced longitudinally on impact, means releasable upon launching of the bomb for holding the starter control rod against rotational and longitudinal displacement and means operable after time-set running of the clockwork mechanism for controlling release of the other firing pin holding lever.

6. In a fuse for bombs, a casing, a clockwork movement in the casing, a firing pin in the casing, a firing pin spring, a pair of levers for holding the firing pin in retracted position, a rotatable

starter control rod engageable with the clockwork movement and with one of the firing pin holding levers, said rod adapted when restrained against rotation to hold the clockwork movement and the lever and adapted when rotated by the clockwork movement to control time release of said lever, means whereby the starter control rod is held against rotation until it has been displaced longitudinally on impact, and means operable after time-set running of the clockwork mechanism for controlling release of the other firing pin holding lever.

7. In a fuse for bombs, a casing, a clockwork movement in the casing, a firing pin in the casing, a firing pin spring, a pair of levers for holding the firing pin in retracted position, means operable after a fixed minimum time of running of the clockwork movement for releasing one of the levers, and means operable after time-set running of the clockwork movement for releasing the other lever.

8. In a fuse for bombs, a casing, a clockwork movement in the casing, a firing pin in the casing, a firing pin spring, a pair of levers for holding the firing pin in retracted position, a member controlling starting of the clockwork movement and driven thereby to control timed release of one lever and means operable after time-set running of the clockwork movement for releasing the other lever.

9. In a fuse for bombs, a casing including a removable cover, a clockwork movement in the casing, a firing pin in the casing, a firing pin spring, a lever for holding the firing pin in retracted position, a member carrying a detonator and movable to position the detonator in line with the firing pin, a rotatable starter control rod having a segment for holding the detonator member and the lever, a gear on said rod meshing with the clockwork movement, means whereby the rod is held against rotation until it has been displaced longitudinally on impact, a first plunger for holding the rod against movement, a spring acting to withdraw the plunger, a second plunger for holding the first plunger in engagement with the rod, a spring acting to remove the second plunger, an arming bolt released on launching of the bomb and holding the second plunger in position to oppose movement of the first plunger, and a bolt controlled by the second plunger and movable to lock the cover to the casing.

10. In a fuse for bombs, a casing, a clockwork movement in the casing, a firing pin in the casing, a firing pin spring, a lever for holding the firing pin in retracted position, a member carrying a detonator and movable to position the detonator in line with the firing pin, a rotatable starter control rod having a segment for holding the detonator member and the lever, a gear on said rod meshing with the clockwork movement, means whereby the rod is held against rotation until it has been displaced longitudinally on impact, a first plunger for holding the rod against movement, a spring acting to withdraw the plunger, a second plunger for holding the first plunger in engagement with the rod, a spring acting to remove the second plunger, an arming bolt released on launching of the bomb and holding the second plunger in position to oppose movement of the first plunger.

11. In a fuse, a casing, a clockwork movement in the casing, a rotatable starter control rod having a gear meshing with the clockwork movement, a member whose movement is controlled by rotation of the starter rod, means whereby the

rod is held against rotation until it has been displaced longitudinally on impact, a first plunger for holding the rod against movement, a spring acting to withdraw the plunger, a second plunger for holding the first plunger in engagement with the rod, a spring acting to remove the second plunger and an arming bolt released at the commencement of flight and holding the second plunger in position to oppose movement of the first plunger.

12. In a fuse, a casing, a clockwork movement in the casing, a rotatable starter control rod having a gear meshing with the clockwork movement, a member whose movement is controlled by rotation of the starter rod, means whereby the rod is held against rotation until it has been displaced longitudinally on impact, and means releasable on launching of the bomb for holding the starter rod against movement.

13. In a fuse, a casing, a removable cover for the casing, a clockwork movement in the casing and including a starting control member, a holding member opposing movement of the starting member, a plunger opposing movement of the holding member, means operable at the commencement of flight for controlling movement of the plunger to release the holding member, and a bolt controlled by the plunger and movable to lock the cover to the casing.

14. In a bomb, a body, a fuse casing threaded on the bomb body, a removable cover for the casing, a pawl carried by the casing, a spring acting to move the pawl into engagement with the bomb body, a movable control member in the casing, a pair of plungers in the casing, a spring for each plunger, a member holding both plungers against the action of their springs whereby one plunger restrains the pawl and the other plunger restrains the control member, means operable at the commencement of flight for controlling release of the plungers, and one of the plungers movable to engage and lock the cover to the casing.

15. In a bomb, a body, a fuse casing threaded on the bomb body, a pawl carried by the casing, a spring acting to move the pawl into engagement with the bomb body, a plunger for holding the pawl clear of the bomb body, a spring acting to remove the plunger from holding engagement with the pawl and means operable at the commencement of flight for controlling release of the plunger.

16. In a fuse, a casing, a removable cover for the casing, a movable member in the casing, a bolt in the casing, and having one end normally restraining the movable member, a spring for moving the bolt out of engagement with the movable member and into engagement with the cover to lock the cover against removal, and means operable at the commencement of flight for controlling release of the bolt.

17. In a bomb, a body, a fuse casing threaded on the bomb body, a removable cover for the casing, means carried by the casing for locking it to the bomb body, and arranged for manual release when the cover is removed, and means operable at the commencement of flight for locking the cover to the casing.

18. In a fuse, a casing, a clockwork movement in the casing and including a timing lever having a segment, a firing pin in the casing, a firing pin spring, a lever for holding the firing pin in retracted position, a rod having a segment on one end for restraining the firing pin holding lever,

and a lever on said rod engaging the segment of the timing lever.

19. In a fuse, a casing, a removable cover for the casing, a clockwork movement in the casing, a setting disk driven by the clockwork movement and having a peripheral recess, a lug on the disk, a timing lever adapted to ride on the periphery of the disk and enter the recess, a stop member, a

spring normally tending to move the stop member into the path of the lug on the disk to oppose movement of the disk to a position where its recess will receive the timing lever, and the cover adapted when attached to the casing to move the stop member to inoperative position.

MARVIN L. MATHISEN.
ARCHIBALD E. REINHARD.
